UNITED STATES PATENT OFFICE

2,375,202

AIRCRAFT TURBINE SUPERCHARGER

Wayne H. Allen, Los Angeles, Calif., assignor to
 General Electric Company, a corporation of
 New York

Application January 7, 1942, Serial No. 425,851

4 Claims. (Cl. 253—39)

The present invention relates to aircraft turbine superchargers of the exhaust gas driven type wherein the exhaust gases are discharged from the turbine buckets directly to atmosphere, and especially to such superchargers when arranged on the aircraft with the axis of the turbine wheel at right angles to the slip stream of the aircraft. With such an arrangement, the slipstream flows transversely of the turbine wheel and tends to force gases issuing from the buckets on the upstream side of the wheel toward the central portion thereof, thus causing heating of the wheel. Also, after-burning of the gases issuing from the turbine wheel may occur.

One object of the present invention is to provide an improved construction and arrangement for protecting the turbine wheel from the hot exhaust gases which effects a smooth and even turning of the gases after they leave the wheel into the slip stream and which interferes to a minimum with radiation of heat from the turbine buckets.

A further object of my invention is to provide an improved arrangement for accomplishing the foregoing which is simple in structure, efficient in operation, and light in weight.

For a consideration of what I believe to be novel and my invention, attention is directed to the following specification and the claims appended thereto.

In the drawing, Fig. 1 is a front view of a supercharger embodying my invention; Fig. 2 is a sectional thereof; and Fig. 3 is a detail view taken on line 3—3, Fig. 1.

Referring to the drawing, 1 indicates the shaft of the supercharger carried in a bearing 2 and having overhung on its end a turbine wheel comprising a central disk 3 on the periphery of which is a ring of buckets 4 having at their outer ends a shroud band 5. Gases from the engine or from the source of supply are directed against the buckets by nozzles 6 which form a part of a nozzle box 7. The exhaust gases are supplied to the nozzle box through a conduit 8. Connected to the nozzle box is a waste conduit 9 in which is mounted a waste gate valve 10 for controlling the operation of the supercharger, as is well understood.

The structure so far described is to be taken as being typical of any suitable gas driven turbine wheel construction. The gases are discharged from the turbine wheel in the direction indicated by the arrows 11. The direction of the slip stream is indicated by arrow 12.

According to my invention, I provide a pro-

tecting disk-shaped shield 13 on top of or on the outboard side of and directly adjacent to the disk 3 of the turbine wheel which is of substantially the same diameter as disk 3, and in connection therewith, I provide a plurality of directing vanes for turning the gases issuing from the turbine wheel buckets through a right angle and directing them smoothly and evenly into the slip stream. In the present instance, I have shown 10 three such vanes, a vane 14 at the upstream or what may be termed the top side of the wheel, and two vanes 15 at the central portion of the wheel, one being located at each side of the wheel. It is to be understood, however, that I may use 15 more than three directing vanes in carrying out my invention.

The shield 13 is illustrated as comprising a cap 16 which is concave-shaped and has a rim 17 bent inwardly and closely spaced with respect 20 to the adjacent surface of the bucket wheel disk, the spacing from the disk increasing toward the center of the cap. Extending across the center of the cap and secured thereto is a wall 18 which defines, with the cap, a conduit 19. The conduit 25 has an inlet opening 20 facing in the direction of the slip stream and located radially beyond the turbine wheel so that no gases issuing from the turbine wheel may enter the cooling conduit 19. At its lower end wall 18 is spaced from cap 16 30 to provide a discharge slot 21 through which air from the slip stream may be discharged against the rim of the bucket wheel at its lower or trailing side relative to the slip stream. Shield 13 is supported, preferably from the nozzle box 7, by 35 two brackets 22 and 23. In the present instance, bracket 23 extends well across wall 18, being attached thereto by a flange 24. It is hollow and, in order to cool it, wall 18 is provided with an opening 25 through which air may enter the 40 space between wall 18 and the wall of bracket 23. Air is discharged from such space through an opening 26. The brackets are attached to the nozzle box by studs 27. The specific construction of shield 13 is not a part of my present invention, it forming subject matter of the application of Chester W. Smith, Serial No. 281,562, filed June 28, 1939 and assigned to the same assignee as the present application. It is to be 45 taken as typical of any suitable shield for a turbine wheel.

The upstream or top vane 14 is in the form of a curved hood which is attached to the nozzle box by spaced ears 28 and studs 30. At its central portion, indicated at 31, it is curved downwardly to substantially the rim of the turbine

wheel disk, well covering the buckets, it being provided with a slot 32 through which the upper end of wall 18 extends. From this central portion, vane 14 tapers outwardly on each side as indicated at 33, finally merging into curved side flanges 34 which terminate at a point 35 well below the wheel and have their lower ends connected together by a back plate 36 having a rearwardly extending flange 37 which partially surrounds the rim of the turbine wheel outside the nozzles and serves to direct outwardly and downwardly gases issuing from the lower side or trailing portion of the turbine wheel. With this arrangement, it will be seen that the buckets are substantially covered by the vane 14 at the top of the wheel and are progressively uncovered toward the center of the wheel, being fully uncovered at approximately the transverse horizontal diameter of the wheel or slightly therebeyond.

Each vane 15 is in the form of a triangular-shaped curved plate attached along its edges to a flange 34 and to cap 16. The curved top 39 of each vane 15 has close clearance with the wheel and, as shown in Fig. 2, extends outwardly so as to become progressively further away from the wheel. It extends downwardly to cover a small arc of buckets, i. e., the arc indicated by the line A. From Fig. 1 it will be seen that vanes 14 and 15 cover the buckets to only a limited extent so that as the bucket wheel rotates, buckets are always exposed directly to the atmosphere so that they may radiate heat to the atmosphere.

In operation, the exhaust gases issuing from the buckets are turned by the vanes 14 and 15 and directed into planes substantially parallel with the plane of the turbine wheel and into the slip stream. The gases issuing from the upper portion of the buckets are turned by the vane 14 and as they flow downwardly they pass over the outer portions of the vanes 15. The gases issuing from the buckets under vanes 15 are turned by such vanes and directed into a plane parallel to the gases flowing from vane 14. By this arrangement, the gases issuing from the turbine wheel are stratified, so to speak, i. e., they are divided into separate planes. This serves to prevent the gases issuing from the upper part of the wheel from flowing in toward the lower part of the wheel. At the same time, the gases are directed smoothly into the slip stream and are carried away by it. Gases issuing from uncovered buckets are picked up and carried along by the gases directed across the wheel by the vanes and by the slip stream. This arrangement for turning the gases interferes to a minimum with the distribution of the slip stream air flow over the turbosupercharger installation and also tends to reduce the aerodynamic drag of the turbosupercharger installation.

As pointed out above, since the vanes cover only a part of the buckets, there are always buckets exposed directly to atmosphere so that heat can be radiated from them to the atmosphere. Thus, the vanes interfere to a minimum with radiation of heat from the buckets.

From another viewpoint, the vanes described above form part of an exhaust hood for directing gases discharged from a bucket wheel of an aircraft turbosupercharger to atmosphere. The exhaust hood has a rear wall with an opening concentrically spaced from the rim of the bucket wheel. The front wall of the hood forms a plurality of vanes for smoothly directing the gases discharged from the bucket wheel to the atmosphere or, from another viewpoint, to reduce the

tendency of the slipstream to interfere with the free discharge of gases from the bucket wheel. As pointed out before, without such exhaust hood the slipstream tends to force the gases discharged from the leading or top portion of the wheel towards the side and trailing portion of the wheel, thus interfering with the discharge of gases from the latter portions. The guide or directing vanes of the exhaust hood cover only a portion of the bucket ring, leaving a substantial portion thereof uncovered and free to radiate heat directly to atmosphere. The guide vanes include a vane covering a top or leading portion of the bucket wheel. This top vane is curved in section, merging gradually into the portion of the exhaust hood that surrounds the bucket wheel and having a radial width decreasing from the top towards opposite sides so that the top portion of the top vane covers the buckets substantially along their entire length whereas the side portions of the top vane cover only the outer ends of the buckets, leaving the inner ends and the roots free to radiate heat to atmosphere.

By using a central shield for the wheel disk in combination with a plurality of vanes of the character shown for directing the gases issuing from the buckets into the slip stream, I am enabled to effect efficient cooling of the wheel and at the same time protect it effectively from the hot gases issuing from the buckets. At the same time, I utilize a structure which is relatively light in weight, important in aircraft applications, and one which is shaped to reduce to a minimum the aerodynamic drag.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. In a supercharger, a turbine wheel comprising a disk and a ring of buckets thereon, a shield for protecting said disk, and a plurality of vanes for directing gases discharged from the bucket ring across the outer surface of the shield, said vanes covering only a portion of the bucket ring and leaving a substantial portion of the buckets uncovered to permit direct heat radiation therefrom to atmosphere, one of the vanes extending over an arc of about 180 degrees, and the other vanes extending over shorter arcs and being secured to the shield.

2. In a supercharger, a turbine wheel comprising a disk and a ring of buckets thereon, a shield for protecting said disk, and a top vane and a plurality of side vanes for directing gases discharged from the bucket ring, said vanes covering a partial area only of the ring of buckets leaving a substantial portion of the ring of buckets free to radiate heat directly to atmosphere, the top vane extending over an arc of about 180 angular degrees and having an outer portion concentrically spaced from and enclosing a portion of the rim of the bucket wheel.

3. In a supercharger, a turbine wheel comprising a disk and a ring of buckets thereon, a shield for protecting said disk, a vane across the top of the wheel and side vanes below the first named vane for directing gases discharged from said bucket ring across the face of the shield, means including the shield for supporting the vanes, the

vane across the top having a radial width decreasing from the top towards the sides, and a rear wall concentrically surrounding the wheel and forming a continuation of the top vane.

4. In an aircraft turbosupercharger arrangement, an exhaust gas operated turbine having a bucket wheel to be mounted with its axis substantially perpendicular to the direction of the aircraft slipstream, a nozzle box for conducting gases to the wheel, and an exhaust hood for directing the gases discharged from the wheel into the slip-stream and for protecting the central portion of the wheel from the heat of the gases, said exhaust hood including a cap concave-

shaped towards the wheel and having a rim closely spaced with the roots of the buckets, a rear wall concentrically enclosing the rim of the wheel, a top vane forming a continuation of the rear wall and extending over an arc of about 180 angular degrees of the wheel, said top vane having a central portion extending radially towards the roots of the respective buckets and portions on opposite sides of the central portion shaped to cover outer portions of the buckets only, and other vanes circumferentially spaced from the top vane and secured between said cap and the rear wall.
